WATER CLOSET

Friedrich Alfred Peter, Palampur, British India

Application January 31, 1944, Serial No. 520,503

3 Claims. (Cl. 4—85)

The invention relates to a water closet intended for use in rural districts, and is to be used in conjunction with a septic tank or drainage system.

Under existing conditions in rural districts where water supply systems and proper drainage are generally not available, the water closet of this invention will serve efficiently in place of the flush system sanitary closets in use in towns.

The invention comprises a water closet in which a truncated, cone shaped pail open at top and bottom is fixed over a chamber. Below the lower outlet of the pail is a basin, which entirely surrounds the lowest portion of the pail without touching it anywhere. The basin is held in such a position that its rim is everywhere 2½ inches above the lower rim of the pail, so that when the basin is filled with water it forms a perfect water seal of 2½ inches height. The basin acts as the moveable bottom of the pail by being firmly attached to a bar which acts as its hinge. This bar extends through the walls of the chamber and turns in bearings which are fitted into the walls of the chamber. Attached to the bar outside the chamber is an operating lever for tilting the basin from the horizontal into the vertical position or vice versa. Attached also to the bar is a lever with a counterweight, this counterweight by the action of gravity brings back the basin to the horizontal position automatically whenever the basin has been forced to the vertical position by the operating lever.

Water from a jug containing a sufficient quantity to fill the basin is poured over the inner sides of the pail flushing it. It collects in the basin filling it and ensuring thereby a perfect water-seal of 2½ inches around the lower portion or bottom rim of the pail. When the water comes from a tank it is made available by the action of a push valve which is inserted in the flushpipe which connects the tank to the pail. In that case the pail is provided with a flush rim which distributes the water over the inner surface of the pail flushing it. The water collects in the basin where it forms the water seal. The water in the basin receives all waste matter when the closet is in use. On tilting the basin downwards bringing it into the vertical position by means of the lever attached to it, as described in detail hereafter, the contents of the basin are discharged into the chamber below, from where a drainpipe leads the discharged water and waste matter into a septic tank or the drainage. The amount of water in the basin ensures also that the basin as well as the chamber are kept clean and flushed.

Should the pail have become soiled during use it is flushed before bringing the basin back into the horizontal position, so that only clean water stays in the basin.

- 5 The basin when forced to the vertical position by the operating lever discharges its contents into the chamber and so to the drain leading from it to the septic tank or drainage. A vent pipe leading off the chamber at its highest point is also provided ensuring that no gases accumulate there. After the basin has been brought back to the horizontal position it is again filled with water, to reform the water seal, and it is then again ready for use.
- 10 15 In an alternative construction in place of the lever and weight used for bringing back the basin automatically to a horizontal position, a lever attached to the bar operating the basin is used, the movement of this lever being controlled by a spring, as described in detail hereafter. The spring used for this purpose may work either by contraction or expansion.

The invention is illustrated in the accompanying drawing in which:

- 20 25 Fig. 1 shows a sectional elevation of the water closet of this invention. Fig. 2 shows a side elevation of the water closet of this invention where a lever and counterweight is used for bringing back the basin to the horizontal position, after the basin has been forced to the vertical position by the operating lever.

- 30 35 Fig. 3 shows a side elevation of the water closet of this invention where a lever and spring is used for bringing back the basin to the horizontal position, after the basin has been forced to the vertical position by the operating lever.

- 40 45 Fig. 4 shows a spring device for holding the operating lever handle and thereby the basin in position.

- In the drawing:
In Fig. 1 the pail 1 open at top and bottom can be of china, iron enamel or some other material and is fixed to the chamber 5 which can be of the same material as the pail or be made of cement concrete. The pail 1 is fixed to the chamber 5 either permanently, when erected on site, or where a factory made article is used it is held in position by screws making it removable to facilitate assembly and inspection. The pail 1 has a seat 2 and a lid or cover 3. The basin 4 which may be of the same material as the pail 1 and which entirely surrounds the lower portion of the pail 1 to a height of 2½ inches when in the horizontal position works in the chamber 5. The

chamber 5 has at its lowest point an outlet or drain 6 which leads to a septic tank or the drainage system (not shown). The chamber 5 has at its highest point a ventilation pipe 7 to ensure that no gases can accumulate within the chamber 5. The basin 4 when in the horizontal position surrounds the bottom rim 1a of the pail 1 and when filled with water this forms the water seal for the chamber 5. The basin 4 is firmly attached to the bar 15 either by resting on a support 4a (see Fig. 3) to which it is secured and which is fixed to the bar 15, or by the bar 15, being square at this point, passing through a square hole in the back of the basin 4, which also ensures, that the bar 15 and the basin 4 move always together. The bar 15 acts as the hinge for the basin 4 and moves in two bearings situated one in each side of the chamber 5. On one side the bar 15 protrudes beyond the wall of the chamber 5 and there the operating lever 8a and the arm or lever of the automatic shutting device, hereafter described, are firmly attached. When the operating lever 8a is pushed downwards by handle 8 into the position 8¹ (shown in dotted lines) the basin 4 is tilted from the horizontal position into the vertical (shown in dotted lines) discharging its contents into the chamber 5 and from there to the outlet or drain 6. The downward movement of the operating lever 8a is stopped by the rest 14. This ensures that the basin 4 does not come into violent contact with the back of the chamber 5. When the operating lever 8a has been brought back into its former vertical position, in which it is firmly held by the lock device 11, hereafter described, the basin 4 assumes the horizontal position. Water is then flushed over the inner surface of the pail 1 which collects in the basin 4 re-forming the water seal, when the closet is again ready for use. Where the water is not poured in by hand from a jug it is made available by the action of a push-valve from a tank (not shown). A flushpipe 12 connects the tank with the pail 1 which is provided with a flush rim 9 for distributing the water over the inner surface of the pail 1.

The basin 4 and operating lever 8a and handle 8 are counterbalanced by an extension bar 16a with weight 16 at the end, the extension bar 16a is fixed to the bar 15 which forms the hinge for the basin 4. The operating lever 8a is also fixed to the bar 15 and the lever 8a when pushed downwards tilts the basin 4 so as to empty its contents into the chamber 5 and from there to the outlet or drain 6. The weight 16 and extension bar 16a attached to the bar 15 counterbalance the weight of the basin 4 and the lever 8a and handle 8, so that when the lever handle 8 is pushed downwards to assume the position shown in the drawing as 8¹ the weight 16 is raised up to assume the position 16¹.

The release of the handle 8 after the basin 4 is emptied causes the weight 16 to descend by gravity and to resume its normal position at 16, and in doing so causes the basin 4 to return to its horizontal position and the operating lever 8a to come back to its vertical position.

To prevent the weight 16 passing its normal position and the operating lever 8a going too far backwards and the basin 4 coming into contact with the lower rim 1a of the pail 1, a stop 17 is fixed in the ground on which the weight 16 comes to rest. This prevents the basin 4 or pail 1 from getting damaged. As an alternative the movement of the lever handle 8a can be stopped by a check bar causing it to stop after passing the lock

device 11, hereafter described thereby also preventing the basin 4 of the pail 1 getting damaged.

The counterweight 16 attached by a lever 16a to the bar 15 which also is the hinge for the basin 4 brings the basin 4 back into the horizontal position by the action of gravity, the same effect can also be obtained through the action of a spring as shown in Fig. 3.

To the bar 15 which acts as a hinge for the basin 4 are attached the operating lever 8a, and the bar or lever 18 which protrudes backwards. To this bar 18 one end of a spring 19 is fixed the other end of spring 19 is fastened to the block 23 securely held in the ground. On tilting the basin 4 downwards into the vertical position through the action of the operating lever 8a the bar or lever 18 moves upwards to the position 18¹ thereby extending the spring 19. When the lever 8a is released the spring 19 contracts and restores the basin 4 to the horizontal position locking the handle of the operating lever 8a behind the spring device 11.

As a further alternative to making use of the force of a contracting spring a similar automatic closing device could also be made by making use of the force of an expanding spring. A lever protruding forwards is firmly fixed to the bar 15 to which the basin 4 is hinged and the operating lever 8a attached. By the downward motion of the operating lever 8a when emptying the basin 4 the attached lever is made to compress a spring. On release of the handle 8 the force of the expanding spring returns or restores the attached lever, the operating lever 8a and the basin 4 to their former positions.

A rest 21 is provided to check the movement of the extension bar 18 in order to prevent the basin 4 coming into sudden and violent contact with the lower rim 1a of the pail 1 on account of the action caused by the spring 19 (contracting or expanding according to the system used) which moves the basin 4 rapidly from the vertical to the horizontal position at the same time bringing back the extension bar 18 from the position at 18¹ to 18. This rest 21 consists of a T shaped iron bar which is fixed vertically to the block 23.

As an alternative a check bar as previously noted could also be inserted behind the lock-device 11, for checking the movement of the operating lever 8a and handle 8 and thereby stopping the basin 4 coming into contact with the rim 1a of the pail 1.

Referring to Fig. 4:

Fig. 4 illustrates a lock device for holding the operating lever 8a in a vertical position by locking the lever 8a when the basin 4 has come to the horizontal position. The lock device consists of a bolt 11 which moves in a tube 12. This tube 12 is closed at one end by a cap 12a, firmly fixed to it, which has a central hole allowing the bolt head to protrude without allowing it to pass through. At the other end the tube 12 is closed by a cap 12b which also has a central hole through which the shaft of the bolt passes. Inside the tube 12 is a spring 13. The passages of the lever handle 8a over the bolt head 11 pushes it back compressing the spring 13. As soon as the lever handle 8a has passed the bolt head 11 this is pushed forward by the spring 13 thereby locking the operating lever 8a. The lock device is held immovable between the flanges of the pail 1 and the chamber 5.

The main advantages of this system over the sanitary seats with flush system as generally used are:

1. That it works on about $\frac{1}{5}$ th of the quantity of water needed by the ordinary flush system and yet achieves the same features of cleanliness and freedom from odour;

2. That on account of the smaller quantity of water used a smaller septic tank is sufficient;

3. That this system both in initial outlay and maintenance is very much cheaper than the ordinary sanitary seat with flush system especially in houses where public water supplies are not available and where a special storage tank would have to be installed;

4. That this system contains no complicated working parts calling for special skill in plumbing and installation;

5. That no danger to the house occurs from bursting pipes where temperatures fall below freezing;

6. That the operation of this system is noiseless which is not the case with other systems usually, a big consideration where many people live in the same house.

Having now particularly described and ascertained the nature of my said invention, and in what manner the same is to be performed, I declare that what I claim is:

1. A sanitary closet comprising a chamber provided with an outlet and a ventilating opening, a pail mounted above the chamber and in communication with the upper end thereof and provided with a flush rim and a water inlet pipe connection therefor, a bar journaled transversely in the chamber having one end projecting ex-

teriorly thereof, a water receiving basin carried by the bar and enclosing the lower end of the pail to form a seal for the chamber, a handle lever connected to the projecting end of the bar for rocking the bar to tilt the basin, an arm also projecting from the bar at an angle to the lever, counterbalancing means associated with the arm and acting to normally maintain the basin in closed position and the lever in an upright position and for returning the parts to such position subsequent to operation thereof, and a resilient check device mounted in the chamber in the path of movement of the lever at a point slightly in advance of the complete raised position of the handle for checking the movement of the handle as it assumes its fully raised position, said check device subsequently acting to facilitate the maintenance of the lever in a raised position.

2. An arrangement as claimed in claim 1 wherein the counterbalancing means is in the form of a weight connected to the outer end of the arm, a stop device for receiving the weight in its closed position, and a further stop device for limiting the outward and downward swinging movement of the handle lever.

3. An arrangement as claimed in claim 1 wherein the counterbalancing means is in the form of a spring, one end of which is connected to the outer end of the arm while the other end is anchored, and a stop device for limiting the outward and downward swinging movement of the handle lever.

FRIEDRICH ALFRED PETER.
